Primary Examiner — Susan Moon Lee(74) *Attorney, Agent, or Firm* — Duane Morris LLP**CLAIM**

The ornamental design for a feeder, as shown and described.

DESCRIPTION

FIG. 1 is a perspective view of a feeder;

FIG. 2 is a top view of the feeder;

FIG. 3 is a bottom view of the feeder;

FIG. 4 is a right side view of the feeder, the left side view being a mirror image thereof;

FIG. 5 is a front view of the feeder, the back view being a mirror image thereof; and,

FIG. 6 is a cross-sectional view of the feeder, as taken along line 6-6 in FIG. 2.

Broken lines and unshaded portions contained within broken lines are not claimed.

1 Claim, 4 Drawing Sheets(56)
